UNITED STATES PATENT OFFICE

ALEXANDER FRASER, OF NEW GLASGOW, NOVA SCOTIA, CANADA.

DESIGN FOR A LAMP-CHIMNEY HEATER.

SPECIFICATION forming part of Design No. 16,090, dated May 19, 1885.

Application filed April 9, 1885. Term of patent 14 years.

To all whom it may concern:

Be it known that I, ALEXANDER FRASER, a resident of New Glasgow, in the Province of Nova Scotia and Dominion of Canada, have 5 invented a new and original Design for a Lamp-Chimney Heater, of which the following is a specification.

My design for a lamp-chimney heater or heating stand for the tops of lamp-chimneys 10 and globes consists in a star-like perforated configuration of the stand, having a circular form, with conical-shaped protuberances on its upper surface, and rounded inner and outer circular margins, substantially as shown and 15 hereinafter described.

Reference is to be had to the accompanying drawings, forming a part of this specification, in which similar letters of reference indicate corresponding parts in both the figures.

20 Figure 1 represents a top view of the stand or heater; and Fig. 2, a transverse section of the same on the line *x-x* in Fig. 1, showing its shape in profile.

Both the outer and inner margins, *a b*, of the 25 stand or heater, which is mainly flat on its upper surface, are of circular form as viewed from above, and of rounded profile or con-

figuration in a transverse and downward direction. Around the central opening, *c*, are a series of equidistantly-arranged apertures, 30 *d*, of triangular configuration, pointing outward. These combined apertures *c* and *d* give an ornamental star-like appearance to the stand or heater, which is further ornamented on its upper surface by a series of 35 conical-shaped protuberances, *e*, arranged between said triangularly-shaped openings *d*. Furthermore, the stand or heater is or may be additionally ornamented by circularly-shaped apertures *f* opposite and beyond the outer 40 angles of the openings *d*.

I claim—

In a design for a lamp-chimney heater, the flat upper surface of the stand, having inner and outer circular margins, *a b*, of rounded profile in a downward direction, triangularly-shaped openings *d* around the central aperture, *c*, and conically-shaped protuberances *e* between said openings *d*, as herein shown and described.

ALEXANDER FRASER.
